REMOTE CONTROLLING APPARATUS

Norman F. Agnew, Stockton, Calif., assignor to
The Union Switch & Signal Company, Swiss-
vale, Pa., a corporation of Pennsylvania

Application May 12, 1930, Serial No. 451,668

70 Claims. (Cl. 246—5)

My invention relates to remote controlling apparatus of the type comprising means for controlling from one point a selected device at a remote point, and for also indicating at said one point the condition of such device. Apparatus embodying my invention is particularly suitable for, though in no way limited to, use in a system of centralized traffic control for railroads providing for the control and indication of railway traffic governing devices, such as switches and signals, from a control station, such as a dispatcher's office.

I will describe two forms of apparatus embodying my invention, and will then point out the novel features thereof in claims.

In the accompanying drawings, Figs. 1 and 2, when placed end to end with Fig. 1 on the left, form a diagrammatic view showing one form of remote controlling apparatus embodying my invention. Fig. 3 is a diagrammatic view showing a modified form of part of the apparatus shown in Fig. 1 and also embodying my invention. Fig. 4 is a detail view illustrating the circuit for controlling the track repeater relay TP shown in Fig. 2. Fig. 5 is a detail view showing the control circuit for the switch indication relay KR illustrated in Fig. 2. Figs. 6 and 7 are diagrammatic views showing the control circuits for relays LH and RH , respectively, illustrated in Fig. 2.

Similar reference characters refer to similar parts in each of the views.

Referring first to Figs. 1 and 2, my invention relates primarily to remote control systems of the step-by-step type comprising equipment located at a central point, such as a dispatcher's office, for controlling and indicating movable devices located at a plurality of other points, such for example as, signal locations or stations distributed along a stretch of track. As here shown, Fig. 2 illustrates the apparatus located at one station and Fig. 1 illustrates so much of the office equipment as is necessary to cooperate with the equipment located at the station shown on Fig. 2. It will be understood, of course, that certain obvious duplications would be made in the office equipment, as indicated in the drawings, to accommodate the system to additional stations similar to that shown on Fig. 2.

The apparatus at the station which is controlled from the office may be of any suitable form, and for purposes of illustration, I have here shown a section of railway track $a-b$ provided with a track circuit including a battery d and a track relay TR . The section $a-b$ contains a switch e of the usual form leading into a siding f . Westbound traffic, that is, traffic moving from right to left, as shown in the drawings, is governed by two signals RB and RA , and eastbound traffic is controlled by two similar sig-

nals LA and LB . As here shown, signals LA and LB are mounted upon the same mast and this mast also carries a call-on arm C . Adjacent the left-hand end of section $a-b$ is an approach section of track $h-a$ provided with a track circuit including a battery d and an approach track relay AR .

The switches, signals, etc., at the station may be controlled in any suitable manner by means forming no part of my present invention. For purposes of illustration, I will assume that the apparatus at the station is controlled by means similar to that disclosed in an application for Letters Patent of the United States, Serial No. 373,675, filed June 25, 1929, by Lloyd V. Lewis, for Remote controlling apparatus, now Patent No. 2,127,691, granted August 23, 1938. For accomplishing this control, the station is provided with a track repeater relay TP which is energized only when the track relay TR is energized, and with a switch indication relay KR which is energized in its normal (left-hand) position or its reverse (right-hand) position according as switch e occupies its normal or its reverse position. As shown in Fig. 4, relay TP is controlled by front contact 175 of track relay TR , so that relay TP is energized only when relay TR is picked up. The switch indication relay KR may be controlled, as shown in Fig. 5, by pole changer contacts 176 and 177 operated by the switch e , in such manner that the relay is supplied with current of one polarity or the other according as the switch occupies one extreme position or the other. The reference characters NWS and IRWS designate switch control relays which operate, through the medium of circuits not shown in the drawings, to move switch e to its normal position when relay NWS is energized and to its reverse position when relay IRWS is energized. Relays LHS and RHS are signal control relays which control signals associated with section $a-b$ in such manner that when relay LHS is energized, signal LA or LB indicates proceed, according as switch e is normal or reverse, provided the track relay TR is energized. In similar manner, when relay RHS is energized, signal RB or signal RA indicates proceed, according as switch e is reverse or normal, provided the track relay TR is energized. In addition, a relay RH is energized when either of signals RB or RA indicates proceed, and a relay LH is energized when either of signals LA or LB indicates proceed. Fig. 6 shows how relay LH may be controlled by circuit controllers 178 and 179 operated by signals LB and LA , respectively, and Fig. 7 shows relay RH controlled by circuit controllers 180 and 181 operated by signals RB and RA , respectively. The call-on arm C is controlled by relay CHS in such manner that when the relay CHS is

energized, the call-on arm is cleared.

Of the relays described in the foregoing paragraph, relays I^{TP} , I^{KR} , I^{NWS} , I^{RWS} , I^{RH} and I^{LH} correspond exactly to the relays having similar reference characters in the Lewis application mentioned above. The remaining relays are controlled in accordance with usual and well known railway signaling practice, and the operation of the relays will be understood without further explanation.

- For the purpose of controlling the apparatus located at the station, there is located at the office a switch control lever I^{p} , a signal control lever I^{q} , and a call-on lever I^{j} for each station.
- As shown in Fig. 1, these parts are distributed to simplify the wiring diagram but in actual practice, all control levers for one station would be grouped together on a single panel which would also carry the indication lamps which will be described hereinafter and which are controlled from the corresponding station.

In general, my invention provides a synchronous selector comprising a chain of counting relays P^{I} , P^{Ia} , P^{2} , P^{2a} , etc., located at the office and arranged to be energized in succession as the controlling and indicating functions proceed. I also provide a second synchronous selector comprising another chain of counting relays which operate in synchronism with the counting chain at the office, but this second chain is distributed throughout the system, certain relays being located at each station so that the stations as units are operated successively in synchronism with the chain of counting relays at the office.

For accomplishing the purposes described above, I provide line wires between the office and the several stations. Line wire I is a common return wire and is connected at the office and at each station with the common terminals C of all control circuits at the corresponding location. In addition, the office is provided with two sources of current of different characteristics. As here shown, these sources are batteries 5 and 6 which are oppositely connected with the common wire I so that the terminals B and N of these batteries, when connected through a conductor with terminal C , deliver to the conductor, currents of opposite polarities. In similar manner, other batteries 5 and 6 are connected with line wire I at the station and their terminals LB and LN may be connected with the circuits shown at the station to provide currents of opposite polarities.

The apparatus also comprises a line wire 2 extending from the office to each of the stations and serving as a stick wire controlling a supplemental selector performing certain functions which will be described in detail hereinafter. In addition to the two wires 1 and 2 , a suitable number of wires are provided for accomplishing the transmission of the control and indication impulses between the office and the stations, and for controlling the step-by-step operation of the synchronous selectors. The number of these additional wires may be varied to meet special conditions, but for purposes of illustration I have shown two wires comprising a stepping wire 3 and a message wire 4 for this purpose.

Before describing the operation of the apparatus, it should be pointed out that, as shown in the drawings, lever I^{j} occupies the position in which the call-on arm indicates stop; lever I^{p} occupies the position in which the switch controlled thereby at the station occupies its nor-

mal position; and the signal lever I^{q} occupies the position for which an eastbound signal determined by the position of the switch, in this case I^{LA} , indicates proceed.

At the station, the switch e occupies its normal position, signal I^{LA} indicates proceed and all of the remaining signals indicate stop. Relay I^{LH} is therefore energized. The approach relay I^{AR} and track relay I^{TR} are both energized so that the track repeater relay I^{TP} is also energized. Relay I^{NWS} is energized and relay I^{LHS} is also energized as will be described hereinafter. The synchronous selectors are normally at rest in a zero position, as shown.

I will now assume that the operator at the office wishes to restore to stop, signal I^{LA} at the station shown in Fig. 2. In order to accomplish this result, he moves the signal control lever I^{q} to its middle position, in which both contacts controlled by arm 7 of this lever are open, and he then reverses a manually operable starting key W . When this happens, current flows from terminal B , through contact $\text{8}-\text{8}^{\text{a}}$ of key W , back contact 9 of a relay KP , and winding of a relay R^{I} to terminal C . Relay R^{I} therefore becomes energized. At the same time a circuit is completed for a relay OH from terminal B , over contact $\text{10}-\text{10}^{\text{a}}$ of key W , and winding of relay OH to terminal C . When relay OH becomes energized, a stick circuit is completed for this relay over its own front contact 11 , and over a back contact 12 of the last relay in the counting chain of relays P^{I} , P^{Ia} , P^{2} , etc., at the office. The purpose of relay OH will be apparent as the description proceeds, but at the present juncture, this relay has no function.

When relay R^{I} becomes energized, a circuit is completed for the first relay P^{I} in the counting chain at the office. This circuit may be traced from terminal B , over front contact 13 of relay R^{I} , back contact 14 of a relay K , back contact 15 of relay KP and winding of counting relay P^{I} to terminal C . Relay P^{I} therefore becomes energized.

The operator may now restore key W to the position in which it is shown in the drawings. When this happens, the circuit previously traced for relay R^{I} is interrupted, so that the relay is deenergized. When contact $\text{8}-\text{8}^{\text{b}}$ of key W is closed, however, a circuit is completed for relay K from terminal B , over contact $\text{8}-\text{8}^{\text{b}}$ of key W , front contact 16 of relay P^{I} , and winding of relay K to terminal C . When relay K picks up it closes at front contact 17 thereon, the circuit for relay KP . Relays K and KP are somewhat slow releasing and as will be explained hereinafter, maintain their front contacts closed until the expiration of a complete operation of the equipment. The energization of relay K also completes a stick circuit for relay P^{Ia} , which passes from terminal B , over front contact 18 of relay K , back contact 19 of relay P^{Ia} , front contact 20 of relay P^{I} , and winding of relay P^{I} to terminal C . Relay P^{Ia} therefore remains energized until relay P^{Ia} , which is the next relay in the counting chain, becomes energized.

Another result of this energization of relay K is that when its front contact 21 closes, terminal B at the office is connected with line wire 2 . This line wire is connected over back contact 22 of a relay S^{I} at the station nearest the office with the winding of relay D^{I} and it follows that when relay K at the office becomes energized, relay D^{I} at the station picks up.

When relay D^{I} at the station becomes ener-

gized the apparatus is in condition for the transmission of the first control impulse. As here shown current of one polarity or the other is supplied, during this impulse, to the stepping line wire 3 at the office in accordance with the position of the switch control lever $1p$, and under the conditions here assumed this control circuit may be traced from terminal B at the office, through arm 23 operated by lever $1p$, front contact 24 of relay $P1$, winding of relay OT, back contact 25 of relay $R1$, line wire 3, front contact 26 of relay $D1$ at the station, back contact 27 of relay $S1$, and winding of relay IWR to terminal C. It will be plain, therefore, that relays OT and IWR become energized in series and the polarity of the current thus supplied to these relays is controlled by the position of the switch control lever $1p$. Since $1p$ occupies its normal position, relay IWR becomes energized in the 20 normal direction so that its polar contact 28 is swung to the left.

The closing of front contact 30 of relay IWR supplies current over back contact 31 of relay $S1$ to the winding of relay $S1$, which thereupon becomes energized and is therefore stuck up over its own front contact 31 and line wire 2, which line wire we have previously explained is supplied with energy over front contact 21 of relay K at the office. When relay $S1$ becomes energized, the circuit previously traced for relay $D1$ is interrupted but relay $D1$ is held energized over back contact 32 of relay $T1$ and front contact 22 of relay $S1$, as will be apparent from the drawings.

It will be noted that the energization of relay $S1$ interrupts the pick-up circuit previously traced for relay IWR at back contact 27 of relay $S1$. Relay IWR is held energized, however, because its front contact 51 is closed and this contact provides a shunt around back contact 27 of relay $S1$.

When relay IWR becomes energized, the closing of front contact 29 of this relay completes a circuit for relay IWP and the latter relay becomes energized.

When relay IWP becomes energized, the opening of back contact 33 of this relay interrupts the stick circuit previously existing for relay $INWS$ and passing from terminal LB, over back contact 33 of relay IWP , front contact 34 of relay $INWS$ and winding of relay $INWS$ to terminal C. The interruption of this stick circuit does not de-energize relay $INWS$, however, because another circuit is now closed for this relay including front contact 33 of relay IWP and normal contact 28 of relay IWR , as will be obvious from the drawings. Relays $INWS$ therefore remains energized and when relay IWP next becomes deenergized, the stick circuit for relay $INWS$ is restored. The 60 switch e at the station therefore remains in its normal position.

When relays $D1$ and IWR at the station close their front contacts, relay IHC is connected with the message line wire 4, but this wire is connected, at the office, through front contact 46 of relay $P1$, with the arms 7 of signal lever $1q$. Since the lever $1q$ occupies its middle position, no current is supplied to the line wire 4 under these conditions and relay IHC remains open. The opening of back contact 37 of relay IWP , however, interrupts the stick circuit previously existing for relay $ILHS$ through the latter relay's front contact 38 and since the pick-up circuit 70 for relay $ILHS$ is open at front contact 39 of

relay $ILHS$, relay $ILHS$ becomes de-energized, thereby restoring signal ILA to stop.

Reverting now to the equipment located at the office, it will be remembered that relay OT becomes energized in series with relay IWR at the station during the first control impulse. When relay OT becomes energized a stick circuit is completed for relay K which may be traced from terminal B, over contact 3-3^b of key W, front contact 39 of relay OT, front contact 40 of relay K and winding of relay K to terminal C. Relay K , and hence relay KP , therefore remain picked up. Furthermore, the energization of relay OT completes a pick-up circuit for relay $P1a$ from terminal B, over front contact 18 of relay K , front contact 41 of relay KP , front contact 42 of relay OT, front contact 43 of relay $P1$ and winding of relay $P1a$ to terminal C. When relay $P1a$ becomes energized, the opening of back contact 10 thereon, interrupts the stick circuit 20 for relay $P1$, and this relay opens its front contact 43 to break the pick-up circuit just traced for relay $P1a$. Relay $P1a$ is held energized, however, over a stick circuit including front contact 18 of relay K , back contact 44 of relay $P2$ and front contact 45 of relay $P1a$. When relay $P1$ releases, the opening of its front contact 24 (shown adjacent lever $1p$), interrupts the control circuit including relays OT and IWR so that these relays become deenergized to terminate the 30 first control impulse. It should be pointed out that this operation of relay $P1$ would also disconnect line wire 4 from its energy at lever $1q$ by the opening of front contact 46 of relay $P1$, if the lever $1q$ were in position to supply current 35 to line wire 4 to give a proceed signal indication as will be described in detail hereinafter. When relays OT and IWR release, the station equipment steps to the next set of relays, to prepare 40 for the transmission of the second control impulse. This is done by means of a circuit which picks up relay $D2$ and passes from terminal LB, over back contact 30 of relay IWR , front contact 47 of relay $S1$, back contact 48 of relay $S2$, and winding of relay $D2$ to terminal C. 45

However, the second control impulse is not transmitted at this time, but the control and indication impulses alternate, and back contacts 51 and 36 of relay IWR which are now closed 50 serve as transmitter contacts to initiate the first indication impulse.

Relay $T1$ at the station and relay $R1$ at the office are now energized in series over the stepping line wire 3 to give at the office an indication of the condition of certain apparatus at the station and in the present instance the indication transmitted, under these conditions, is a track indication which informs the operator at the office concerning the condition of section $a-b$. 60 For this purpose the indication circuit including relays $T1$ and $R1$ is supplied with current of one polarity or the other at the station according as relay ITK is energized or deenergized. As shown in the drawings, relay ITK is deenergized 65 because relay ITP is energized when the section $a-b$ is unoccupied, and so the indication circuit may be traced from terminal LN at the station, over back contact 49 of relay ITK , winding of relay $T1$, front contact 50 of relay $S1$, back contact 51 of relay IWR , front contact 23 of relay $D1$, line wire 3, back contact 52 of relay $P1$, front contact 54 of relay $P1a$ and winding of relay $R1$ to terminal C. The current thus supplied to relay $R1$ energizes this relay in its reverse direction 70 75

tion so that the polar armature 54 of this relay is swung to the right. Under these conditions, the pick-up circuit for relay ORT¹ remains open, although front contact 55 of relay P^{1a} and front contact 56 of relay R¹ are closed. Relay ORT¹ therefore remains deenergized and lamp 57 remains dark to indicate that the section at the corresponding station is unoccupied.

At the same time that the track indication is delivered over the stepping line wire 3, another indication is delivered over the message line wire 4. As here shown, the second indication is a switch indication, and current of one polarity or the other is supplied to line wire 4, depending upon the position of relay IKR, which it will be remembered responds to the position of switch e at the station. Since the switch is now normal, the switch indication circuit may be traced from terminal LB at the station through normal contact 58 of relay IKR, front contact 59 of relay IKR, winding of relay IWD, front contact 60 of relay S¹, back contact 36 of relay IWR, front contact 35 of relay D¹, line wire 4, front contact 61 of relay P^{1a}, back contact 62 of relay P¹, and winding of relay R² to terminal C. Relays IWD and R² are energized in the normal direction so that the polar armatures of these relays are swung to the left. When relay R² becomes energized, a pick-up circuit is completed for relay ONW¹, from terminal B, over front contact 63 of relay R², normal contact 64 of relay R², front contact 65 of relay P^{1a} and winding of relay ONW¹ to terminal C. When relay R² next becomes deenergized, the pick-up circuit just traced is interrupted but the relay ONW¹ will be held in its energized condition over a stick circuit including back contact 66 of relay P^{1a} and front contact 67 of relay ONW¹. Under these conditions, that is, with relay ONW¹ energized, current is supplied to an indication lamp 68, over front contact 69 of relay ONW¹, thereby lighting the lamp to indicate that switch e at the station occupies its normal position.

The indication impulse transmitted over line 3 is also a stepping impulse, and when relay R¹ becomes energized, it closes a pick-up circuit for relay P², from terminal B, over front contact 13 of relay R¹, front contact 14 of relay KA, front contact 70 of relay P^{1a}, and winding of relay P² to terminal C. Relay P² therefore becomes energized, breaking the stick circuit for relay P^{1a} and completing its own stick circuit through contact 18 of relay K, back contact 71 of relay P^{2a}, and front contact 72 of relay P².

It will be noted that if relay P^{1a} should release before the indication impulse is terminated, the pick-up circuit previously traced for relay R¹ is opened at contact 54 of relay P^{1a}, but relay R¹ would be held energized because its front contact 25 provides a shunt around contact 54.

At the station, when T¹ became energized, the stick circuit previously traced for relay D¹ was interrupted at back contact 32 of relay T¹ so that relay D¹ became deenergized. When relay D¹ releases, the circuits through relays T¹ and R¹ and through relays IWD and R² are opened to terminate the first indication impulse, and back contacts 26 and 35 of relay D¹ connect the line wire 3 with the next group of apparatus. As here shown this next group is a part of the apparatus at the same station, but this arrangement is not essential. In order to place the equipment in condition to receive the second control

impulse, the operation of a supplementary selector relay IM at the station is required, which relay is energized by current delivered over a front contact of relay OH at the office, which it will be remembered was actuated by operation of the key W. The contact of relay OH which effects this result is numbered 73 and is located in the drawings immediately below the signal control lever 1q. Relay P^{1a} at the office releases shortly after the first indication impulse is terminated, and when relay P^{1a} releases, the circuit for relay IM becomes closed. This circuit may be traced from terminal B, through front contact 73 of relay OH, front contact 74 of relay P², back contact 61 of relay P^{1a}, line wire 4, back contact 35 of relay D¹, front contact 75 of relay D², back contact 76 of relay S², and winding of relay IM to terminal C. Relay IM picks up and initiates the second control impulse by completing the circuit for relays CT and ICH which are energized in series over line wire 3, the polarity of the current supplied to this circuit being controlled by the position of the call-on lever 1j. As shown in the drawings, this circuit may be traced from terminal B, over arm 77 controlled by lever 1j, front contact 78 of relay P², back contact 79 of relay P^{1a}, winding of relay OT, back contact 25 of relay R¹, line wire 3, back contact 26 of relay D¹, front contact 80 of relay D², back contact 81 of relay S², front contact 82 of relay IM, and winding of relay ICH to terminal C. Relay ICH therefore becomes energized, and the polarity of the current supplied to this relay is such that the polar armature is swung to the left. When relay ICH becomes energized, it picks up relay S² over front contact 83 of relay ICH, and back contact 84 of relay S². When relay S² is energized, it completes a stick circuit by virtue of which it is subsequently held in its energized condition over its own front contact 84, front contact 47 of relay S¹, and back contact 38 of relay IWR. It will be observed that the energization of relay S² interrupts the pick-up circuit previously traced for relay ICH at back contact 81 of relay S². Relay ICH is held energized, however, because its front contact 85 is closed and this contact provides a shunt around back contact 81 of relay S².

When relay S² becomes energized, the circuit previously traced for relay D² is interrupted, but relay D² is now held energized over back contact 86 and relay T² and front contact 48 of relay S². Since relay ICH is energized in the normal direction so that its polar armature 87 is swung to the left, the circuit for relay ICHS remains open, and this relay remains deenergized so that the call-on arm 1C at point a continues to display its stop indication.

The purpose of relay IM is to permit the apparatus to step forward to the next location automatically, since, as will be described herein-after, the normal operation of the apparatus when initiated from an outside station is to operate only until that particular station has returned its indication. When operation is initiated at the office, however, it is usually desirable to step completely through the equipment so that indications are received of the condition of all apparatus controlled from the office. For this purpose, the relay OH is arranged to be energized when the key W is operated and to remain energized until the final counting relay has been operated.

When relay OT becomes energized by the second control impulse, as explained above, the circuit is again closed for relay K which insures

that this relay will remain picked up. Furthermore, the energization of relay OT completes a pick-up circuit for relay P2a similar to the circuit previously traced for relay P1a, as will be understood without tracing this circuit in detail. When relay P2a becomes energized, the opening of its back contact 71 interrupts the stick circuit for relay P2 so that relay P2 becomes de-energized and releases. When this happens the opening of front contact 78 of relay P2 (adjacent lever 17) and the opening of front contact 74 of relay P2 (adjacent lever 19) interrupt the control circuits previously described and terminates the second control impulse. Relays 1M, 1CH and OT then become deenergized. When relay 1CH releases, it closes its back contact 83, thereby connecting terminal LB with line wire 2A, extending to the next station and thus picking up the relay at that station which corresponds to relay D1 at the station shown on Fig. 2. This operation, of course, prepares the apparatus at this next station to receive the succeeding impulses in the same manner as described in connection with the station shown in Fig. 2. When relay 1CH releases, it initiates the second indication impulse by completing a circuit for relay T2 at the station and relay R1 at the office in series over line wire 3. The polarity of the current supplied to this circuit is controlled in accordance with the condition of the approach section *h—a*, and as here shown is governed by relay 1AK controlled by the approach track relay 1AR. As shown in the drawings, relay 1AR is energized, so that relay 1AK is deenergized and the circuit then closed passes from terminal LN, through back contact 88 of relay 1AK, winding of relay T2, front contact 89 of relay S2, back contact 85 of relay 1CH, front contact 80 of relay D2, back contact 26 of relay D1, back contact 90 of relay P2, front contact 91 of relay P2a, and winding of relay R1 to terminal C. The polarity of the current supplied to this circuit is such that relay R1 is energized to swing its polar armatures to the right so that relay ORA1 remains deenergized, even though front contact 56 of relay R1 and front contact 92 of relay P2a becomes closed. Lamp 93 therefore remains dark to indicate that the approach section *h—a* at the station is unoccupied. When relay R1 becomes energized, relay P3 at the office is energized over front contact 13 of relay R1, front contact 14 of relay K and front contact 94 of relay P2a. Relay P3 then picks up and is subsequently stuck up over back contact 95 of relay P3a, while relay P2a becomes deenergized. Even if relay P2a releases, however, relay R1 will be held energized over its front contact 25 and line wire 3, until the impulse is terminated by the release of the station relay D2 and the opening of front contact 80 of that relay.

As pointed out hereinbefore, all signals at the station shown on Fig. 2 are at stop, so that relays 1RH and 1LH are both deenergized. As a result, no circuit is completed for relay R2 when the circuit previously traced for relays T2 and R1 is closed. As a result, no pick-up circuit is closed for relay ORH1 at the office and since the stick circuit for this relay is interrupted at back contact 96 of relay P2a, when relay P2a becomes energized, relay ORH1 becomes deenergized to extinguish lamp 97. Back contact 98 of relay ORH1 and back contact 99 of relay ORH1 are then both closed, so that lamp 100 is lighted to indicate that all of the signals at the station indicate stop.

When relay T2 became energized in series with relay R1, the stick circuit for relay D2 over back contact 86 of relay T2 was opened, so that relay D2 is now deenergized and releases, terminating the impulse. When back contact 80 of relay D2 closes, the line wire 3A is completed to the next station to the right of that shown on Fig. 2. The first control impulse for that station is initiated when relay P2a closes its back contact in the circuit for relay OT, and the operation at this station will be understood from the previous discussion of the apparatus shown on Fig. 2.

All of the remaining stations operate in succession in a similar manner until the last station has been controlled and has indicated its condition to the office. When this happens, the final counting relay at the office becomes energized, thereby opening its back contact 12 and breaking the stick circuit for relay OH at the office. Relay OH then releases and since front contact 73 of relay OH is then open, no control circuit is closed to energize relay OT. The slow release relays K and Kp then become deenergized and release successively, and when relay K releases, it de-energizes relay S1. The release of relay S1 de-energizes relay S2 and all corresponding relays are deenergized in succession so that the apparatus is restored to its normal condition.

It will be plain from the foregoing that if the key W at the office is operated, the equipment is set into operation to transmit a series of stepping impulses which serve alternately as control and indication impulses to condition all of the devices at the several stations in succession in accordance with the positions of the control levers corresponding thereto at the office, and also to indicate at the office the condition of the several devices. This is performed by sending out a first control impulse from the office to a first station, then sending an indication impulse from that station, then sending another control impulse from the office and another indication impulse from the station, then stepping to the next station, and repeating this process until all stations in order have been controlled and have indicated.

It should be pointed out also that if the control levers at the office occupy different positions from those previously assumed, the actual control at the station may be different, although the general plan of operation remains the same. For example, I will assume that the signal control lever 1q is moved to its "RH" position so that arm 7 engages the contact connected with terminal N. Under these conditions, when relay 1WR at the station shown on Fig. 2 becomes energized, relay 1HC at the station is energized during the first control impulse to swing its polar armature to the right. Relay 1WP will be energized under these circumstances, and a circuit is then completed, over front contact 37 of relay 1WP, and front contact 101 of relay 1HC to energize relay 1HP. Relay 1HP is subsequently stuck up over its own front contact 102 and front contact 37 of relay 1WP. Since relay 1HC is energized in its reverse direction so that polar armature 103 is swung to the right, current is supplied to relay 1RHS over front contact 39 of relay 1HP and reverse contact 103 of relay 1HC. Relay 1RHS then becomes energized, and is subsequently stuck up over its own front contact 104 and back contact 37 of relay 1WP after the latter relay becomes deenergized. Since relay 1RHS is energized, signal 1RB or 1RA indicates proceed, depending upon the position of switch e.

In the present instance, since switch e is normal, signal !RA would be moved to the proceed position.

In similar manner, if signal control lever $1q$ is restored to the position in which it is shown in the drawings so that arm 7 engages the contact connected with terminal B , and the apparatus is then set into operation, relay !HC will be energized during the first control impulse to swing its polar armature to the left when relay !D1 becomes energized. When this happens, relay !HP will become energized, as explained hereinbefore, and a pick-up circuit will then be closed for relay !LHS over front contact 39 of relay !HP and normal contact 103 of relay !HC . Relay !LHS then becomes energized and is subsequently stuck up after relay !WP becomes deenergized, over back contact 37 of relay !WP and front contact 38 of relay !LHS . When relay !LHS is energized, signal !LB or !LA indicates proceed, depending upon the position of switch e , and as here shown, with switch e normal, signal !LA indicates proceed.

Similarly, I will assume that switch control lever !p occupies its reverse position, so that arm 23 engages the contact connected with terminal N . If the apparatus is now set into operation to control and indicate the several stations, when relays OT and !WR become energized after relay !D1 becomes energized, the polarity of the current supplied to relay !WR swings the polar contact 28 of this relay to the right. When relay !WP becomes energized, current is then supplied over front contact 33 of relay !WP , reverse contact 28 of relay !WR , and winding of relay !RWS to terminal C . When relay !WP next becomes deenergized, a stick circuit is completed for relay !RWS , over back contact 33 of relay !WP and front contact 105 of relay !RWS . When relay !RWS is energized, the switch e is operated to its reverse position.

The switch, may of course, be restored to its normal position by restoring the lever !p to its normal position in which it is shown in the drawings and operating the key W , under which conditions, the apparatus will operate as previously described to pick-up a stick relay !NWS and restore the switch to its normal position.

The call-on lever !j is customarily employed to clear a call-on arm, such as !C , of a signal located at point a on Fig. 2 when the proper controls are set up to clear one of the signals, such as !LA or !LR , but when such signal is prevented from assuming its proceed position by some dangerous condition such as the presence of a train in section $a-b$. For example, I will assume that the lever !q occupies its "LH" position, as shown in the drawings, so that relays !HS and !LH at the station are energized, but that because of a train in section $a-b$, the signal !LA is prevented from clearing. If, now, the operator at the office moves lever !j to the right, connecting arm 77 attached to terminal N , he may cause the call-on arm !C at the station to indicate proceed. This is accomplished as follows: When relay OT at the office and relay !CH at the station become energized in series during the second control impulse following the energization of relays D2 and !M , the current supplied to the circuit including relay !CH is of such polarity that relay !CH swings its polar contact 87 to the right. When this happens, a circuit is closed from terminal LB , over contact 87 of relay !CH , winding of relay !CHS , front contact 106 of relay !LHS to terminal C . Relay

!CHS then becomes energized and clears signal !C by means forming no part of my present invention.

In the previous discussion I have assumed that the apparatus is set into operation by manipulation of the key W at the office. The operation can also be started automatically in response to any change in the condition of a movable device at any station. In explaining this feature of my invention, I will first assume that with the apparatus in the condition shown in the drawings, a train enters section $a-b$ at the station shown on Fig. 2. When this happens, relay !TR becomes deenergized. The opening of front contact 175 of relay !TR breaks the circuit for relay !TP (see Fig. 4), and the latter relay then becomes deenergized. When relay !TP becomes deenergized, a pick-up circuit is completed from terminal LB , over back contact 107 of relay !TP , back contact 108 of relay !D1 , and winding of relay !TK to terminal C . Relay !TK then becomes energized and is subsequently held energized to store the "track-occupied" indication until transmitted, over a stick circuit which may be traced from terminal LB , over front contact 109 of relay !TK , back contact 110 of relay !TD , and winding of relay !TK to terminal C . When relay !TK becomes energized, a preliminary or starting circuit is closed for relay R1 at the office, which circuit originates at the station and may be traced from terminal LB , over front contact 111 of relay !TK , back contact 112 of relay !TD , back contact 113 of relay S1 , back contact 26 of relay !D1 , line wire 3 , back contact 114 of relay K , back contact 9 of relay KF , and winding of relay R1 to terminal C . Relay R1 at the office then becomes energized, picking up relays P1 and K as explained hereinbefore. When relay K becomes energized, a stick circuit is closed for relay P1 , and relay D1 at the station shown on Fig. 2 becomes energized. The circuit for relay R1 is opened at back contact 26 of relay !D1 , and relay R1 releases, completing the circuit for the first control impulse through relays OT and !WR . From this point on, the operation of the equipment is the same as that described hereinbefore, except that when relays R1 and T1 become energized in series, the circuit now includes front contact 49 of relay !TK , so that the polarity of the current supplied to the circuit is such as to energize relay R1 in the normal direction to swing its polar contacts to the left. At the time relay R1 becomes energized, relay P1a is also energized so that a circuit is completed from terminal B , over front contact 56 of relay R1 , normal contact 54 of relay R1 , front contact 55 of relay P1a , and winding of relay ORT1 to terminal C . When relay P1a next becomes deenergized a stick circuit is completed for relay ORT1 , over back contact 114 of relay P1a , and front contact 115 of relay ORT1 . Front contact 116 of relay ORT1 is thereby held closed to light lamp 57 and indicate that the section $a-b$ at the station is occupied by a train.

Furthermore, when relay T1 becomes energized, a pick-up circuit is completed for relay !TD , from terminal LB , through front contact 117 of relay D1 , front contact 118 of relay T1 , front contact 119 of relay !TK and winding of relay !TD to terminal C . Relay !TD then becomes energized, and is subsequently stuck up after the deenergization of relay T1 over front contact 120 of relay !TD and back contact $32a$ of relay T1 . It should be noted that when relay T1

5 TD becomes energized, it opens, at back contact 110 thereon, the stick circuit previously traced for relay TK , but relay TK is now held up over a temporary stick circuit including its own front contact 109 and front contact 108 of relay D1 . When relay D1 becomes deenergized, this temporary stick circuit is interrupted, but relay TK is subsequently held up as long as relay TP is deenergized, over back contact 107 of relay TP . Under these conditions, then, relays TK and TD are both energized so that the starting circuit through back contact 113 of relay S1 is open.

10 If now the train passes out of section $a-b$, relay TP again becomes energized, thereby deenergizing relay TK and again completing the starting circuit over back contact 111 of relay TK and front contact 112 of relay TD . Under these conditions, the apparatus is again set 15 into operation, but when relays T1 and R1 are energized in series, the circuit will include back contact 49 of relay TK , so that relay R1 will be energized in the reverse direction. Under these conditions, the opening of back contact 114 20 of relay P1a interrupts the stick circuit for relay ORT1 , and since the pick-up circuit for this relay is open at normal contact 54 of relay R1 , relay ORT1 remains deenergized and lamp 57 is extinguished to indicate that the train has left 25 the corresponding track section. Furthermore, when relay T1 becomes energized, the stick circuit for relay TD is interrupted at back contact 32a of relay T1 , so that relays TK and TD are now both deenergized and the other starting circuit controlled thereby, is open.

30 The apparatus may be set into operation also by any change in the position of the switch e which will be reflected in the position of the switch indication relay IKR . For example, I 35 will assume that with the parts occupying the positions in which they are shown in the drawings, relay IKR becomes energized in its reverse position to swing its polar contacts to the right. When this happens, a circuit is completed from 40 terminal LB , over front contact 121 of relay IKR , polar contact 122 of relay IKR , polar contact 123 of relay IWD , back contact 113 of relay S1 , back contact 26 of relay D1 , and thence over line wire 3 to the office, as described hereinbefore. The 45 starting circuit thus closed sets the apparatus into operation in the manner previously described. When relays IWD and R2 are energized in series, following energization of relays D1 and S1 and deenergization of relay IWR during 50 the first indication impulse, the polarity of the current supplied to the circuit is such that relay R2 becomes energized in the reverse direction to swing its polar contact 64 to the right. When this happens, a pick-up circuit is completed 55 over front contact 63 of relay R2 , reverse contact 64 of relay R2 , front contact 124 of relay P1a and winding of relay ORW1 to terminal C. Relay ORW1 then becomes energized, and when relay P1a again becomes deenergized, relay ORW1 is stuck up over its own front contact 60 60 and back contact 66 of relay P1a . In the meantime, relay ORW1 has been energized and since relay ORW1 is now energized, current is supplied over its front contact 126 to light lamp 65 65 70 75 127, thereby indicating that the switch e on Fig. 2, occupies its reverse position. Furthermore, the current supplied to the circuit including relays IWD and R2 also swings the polar armature 123 of relay IWD to the right into coincidence with the polar armatures of relay IKR , thereby

8 breaking the starting circuit previously described. If, now, the switch e is restored to its normal position, relay IKR is again operated out of agreement with relay IWD and a starting circuit is closed to set the apparatus into operation. Under these conditions, the indication received at the office again energizes relay ONW1 to light lamp 68 and deenergizes relay ORW1 to extinguish lamp 127.

9 It should be pointed out that if for any reason the switch at the station occupies an intermediate position so that relay IKR is deenergized, no current is supplied to the circuit when relays IWD and R2 are connected in series. As a result, relay R2 remains deenergized, while relay P1a picks up to break the stick circuit for either of the relays ONW1 or ORW1 thus extinguishing both of the lamps 68 and 127 to indicate that the switch e at the station shown on Fig. 2 occupies an intermediate position.

10 The relays IAK and IAD are arranged to provide an approach indication, under the control of relay IAR in the same manner as relays TK and TD provide a track indication under the control of relay ITR . Thus when relay IAR picks up or releases, a starting circuit is closed when relays IAK and IAD are out of agreement and the indication transmitted when relays T2 and R1 are energized in series, is controlled by contact 88 of relay IAK to govern the polarity 15 of the current supplied to the circuit and hence to determine whether or not relay ORAI at the office is energized to light lamp 93. This feature of my invention will immediately be apparent from the previous discussion of the reception of 20 the track indication.

25 The apparatus is also constructed to complete the starting circuit and initiate operation of the equipment upon any change in signal indication. Any such change in signal indication picks up 30 relay IHK , and when this happens, current flows from terminal LB , over front contact 128 of relay IHK , back contact 129 of relay S2 , back contact 35 30 of relay D2 , back contact 26 of relay D1 , line wire 3 and thence as before to the apparatus at the office. When this starting circuit is closed, the operation of the equipment is initiated, and this operation continues in the same manner as when any other starting circuit is completed.

40 Relay IHK is controlled by relays IRH and ILH and also by a back lock relay IX . Relay IX is energized only when relays IRH and ILH are both deenergized, but when the condition of either of relays IRH or ILH changes, relay IHK is energized for a brief interval over a pick-up circuit 45 and is subsequently stuck up over its own front contact 130 and back contact 131 of relay S2 until the corresponding indication has been delivered. For example, as shown in the drawings, relay IRH is deenergized and relay ILH is 50 energized, as would be the case when signal ILA indicates proceed. If, now, relay ILH becomes deenergized, as when signal ILA is restored to the stop position, a circuit is completed over back contact 132 of relay IRH and back contact 133 55 of relay ILH to relay IX , which then becomes energized. Before the relay IX opens its back contact, however, a pick-up circuit is completed from terminal LB , over contact 132 of relay IRH , back contact 133 of relay ILH , back contact 134 60 of relay IX , and winding of relay IHK to terminal C. Relay IHK is therefore energized and is subsequently held up over the stick circuit described hereinbefore. When relay IHK becomes 65 70 75 80 85 90 95 energized, the closing of front contact 128 com-

pletes a starting circuit and sets the apparatus into operation. Since the office relay OH has not been energized, relay IM does not become energized and its contact 32 in the pick-up circuit for relay ICH remains open. This contact, however, is now bridged by contact 146 of relay H1 and relay ICH picks up in response to the second control impulse, as previously described. Relay ICH energizes relay S2 which picks up and opens its back contact 131 in the stick circuit for relay IHK. Relay IHK therefore releases so that the starting circuit will remain open after the apparatus completes its operation. Since relays ILH and IRH are both deenergized, there will be no signal indication impulse transmitted over line 4 when relay ICH becomes deenergized and relays OLH1 and ORH1 at the office both become deenergized to light lamp 100.

With the apparatus in its normal condition, as shown, if relay IRH becomes energized, as would be the case if signal IRA or IRB is caused to indicate proceed, the circuit for relay IX would be broken, but before the latter relay could open its front contacts, a pick-up circuit would be closed for relay IHK over front contact 132 of relay IRH, front contact 135 of relay IX and winding of relay IHK to terminal C. The energization of relay IHK would close the starting circuit as before to start the system into operation. Since relay IRH is now energized, however, the indication circuit is completed when relay ICH becomes deenergized while relay S2 is energized, and current flows from terminal LN, over front contact 136 of relay IRH, front contact 137 of relay S2, back contact 138 of relay ICH, front contact 75 of relay D2, back contact 35 of relay D1, line wire 4, front contact 139 of relay P2a, back contact 140 of relay P2, and winding of relay R2 to terminal C. The polarity of the current supplied to this circuit is such that relay R2 swings its polar contact 64 to the right and current then flows from terminal B at the office, over front contact 63 of relay R2, reverse contact 64 of relay R2, front contact 141 of relay P2a and winding of relay ORH1 to terminal C. Relay ORH1 then becomes energized and is subsequently stuck up over back contact 96 of relay P2a and front contact 142 of relay ORH1. As a result, lamp 143 is lighted over front contact 144 of relay ORH1 to indicate that a westbound signal at the associated station indicates proceed.

The operation of the apparatus when relay ILH becomes energized is similar to that just described for the energization of relay IRH, except that the circuit for relay R2 then includes front contact 145 of relay ILH instead of front contact 139 of relay IRH. The polarity of the current supplied to relay R2 is thus reversed so that relay OLH1 becomes energized and is stuck up over a back contact of relay P2a to light lamp 97 and indicate that an eastbound signal indicates proceed at the associated station.

There is one major difference between the operation of the apparatus when started at the office and the operation of the apparatus when started by a change in indication at the station. As shown in Figs. 1 and 2, when started at the office by operation of key W, the equipment steps through all of the stations in succession until the final counting relay has been operated.

As illustrated in Figs. 1 and 2, when the operation is initiated from a station, the equipment operates until that particular station has been reached, whereupon the apparatus stops and

returns to its normal condition. To illustrate this feature, I will assume that a track indication from the station, shown in Fig. 2, is initiated by the deenergization of relay ITP. The system then operates as previously described until the circuit over which relays R1 and T1 are energized in series is interrupted. After this happens, the next step in the sequence of operations must be the energization of relay ICH over line wire 3. It will be apparent, however, that the circuit through relay ICH is open at front contact 82 of relay IM and also at front contact 146 of relay H1. Since this control circuit can not be completed, relay OT at the office remains deenergized, whereupon relays K and KP become deenergized, relays S1 and S2 become deenergized, and the apparatus is returned to its normal condition.

It should be observed, however, that when any starting circuit is closed at a station, current is supplied from terminal LB to the line wire 3 at that station. At any location between this station and the office, a relay corresponding to relay H1 on Fig. 2, will be energized to permit the equipment to step out as far as the station at which the indication originated. For example, if a station to the right of the apparatus, shown on Fig. 2, has initiated an indication, the line wire 3A will be connected with a source of current so that when relay D2 becomes energized, current flows from terminal LB of the source over this line wire 3A, over front contact 147 of relay D2 and back contact 148 of relay H1 through the winding of relay H1 to terminal C. Relay H1 then becomes energized, and a stick circuit for the relay is completed from terminal LB, over front contact 149 of relay D2 and front contact 143 of relay H1, through the winding of relay H1 to terminal C. Under these conditions, it will be seen that front contact 146 of relay H1 is closed to complete a shunt circuit around the open front contact 82 of relay IM in the control circuit for relay ICH. The circuit including relays ICH and OT in series will then be energized to permit the apparatus to operate to the next station, and to each successive station until the point is reached at which the starting impulse originated.

In the modification shown in Fig. 3, I have arranged the apparatus in such manner that when the operation is started from the office the equipment functions only until the selected station which it is desired to control has been reached, and then the apparatus returns to its normal condition. This is accomplished by replacing the single key W of Fig. 1 with a plurality of starting keys OW1, OW2, OW3, etc., one for each panel at the office. Furthermore, the relay OH of Fig. 1 is replaced by a plurality of relays OH1, OH2, OH3, etc., one controlled by each starting key. With this arrangement the contact 73 of relay OH shown in Fig. 1 which operates to step from station to station when the operation is initiated at the office is replaced by front contacts 201, 202, 203, etc., of relays OH1, OH2, OH3 respectively.

If key OW1 is operated to actuate the equipment only up to the corresponding station, the starting circuit for relay R1 is closed over contact 204 and the system set into operation in the same manner as previously described in connection with Fig. 1. At the same time, the operation of contact 205 of key OW1 completes a pick-up circuit for relay OH1, which becomes energized, and is thereafter stuck up over its own front con-

tact 206 and back contact 207 of relay P2a, after the key OW1 is released.

Now at the time that the second control impulse is sent to the station corresponding to key 5 OW1 (in this case the station illustrated on Fig. 2), relay P2 is energized. Since relay OH1 is now energized, current is supplied to line wire 4 at the office over front contact 201 of relay OH1 and front contact 74 of relay P2 to energize relay 1M, 10 consequently the second control impulse is received by relay 1CH and subsequently the equipment steps to the next station. But, at the termination of the second impulse, relay OT picks up and energizes relay P2a as described hereinbefore. When relay P2a picks up, the stick circuit for relay OH1 is interrupted, and the latter relay becomes deenergized. Line wire 4 can not thereafter again be supplied with current for stepping from station to station unless another 15 relay controlled by another starting key is energized, and the apparatus therefore drops out and restores to normal after the transmission of the first indication impulse from the next station.

With the modification shown in Fig. 3, therefore, the system operates fully only as far as the station which is selected by the starting key which is operated, and thus materially decreases the average time in which the line is in use for delivering control codes.

30 It should be pointed out that the control of the supply of current to line wire 4 by the relays OH1, OH2, etc., is not essential, as these relays could be utilized to govern any control or indication circuit for the corresponding panel, which is required to be operated to step from station to station.

It will be observed that in some instances a circuit is controlled by both the front and back contacts of a relay. If it is desirable that the circuit through these contacts be uninterrupted when the relay moves from its deenergized to its energized position, the contacts may be arranged to close the front contact before the back contact opens. Contacts adjusted in this way are 40 usually called "continuity transfer contacts" and I prefer to so adjust contact 31 of relay S1, contact 34 of relay S2, and contact 148 of relay H1 as shown in Fig. 2, and the corresponding contacts at other stations.

50 It will be observed that in many instances I have shown rectifiers connected between one terminal of a relay and the terminal C. These rectifiers are utilized to shunt the current induced in the relay windings when the relay circuit is opened and tend to make the relays slightly slow releasing and also reduces sparking at the contacts which open the relay circuits.

I have also illustrated a resistor 160 and a condenser 161 connected in series across front 60 contact 26 of relay D1 to reduce sparking at this contact, and a similar arrangement is also provided for front contact 30 of relay D2.

One advantage of apparatus embodying my invention is that every station is provided with 65 apparatus which is identical with the apparatus located at every other station, irrespective of the total number of stations in the system. That is to say, in order to increase the number of stations controlled from a single office, all that 70 is necessary is to extend the four line wires 1, 2, 3 and 4 to the stations which are to be controlled, install at each of such stations, apparatus similar to that shown on Fig. 2, and add to the counting chain at the office, additional relays similar to relays P1, P1a, etc., to 75

accommodate for the increased number of steps involved in complete operation of the system.

Another advantage of apparatus embodying my invention is that the system functions in precisely the same way whether started from the office or from a station and the system must operate in the manner intended so that control impulses and indication impulses alternate on the line wires, connecting the stations successively with the office and if the parts do not function in the proper sequence, the apparatus will drop out and start over from the beginning.

Another advantage of apparatus embodying my invention is that since local batteries are utilized at each station, comparatively small voltages may be employed satisfactorily. Excessive voltages are not required, because it will be noted that under no conditions are more than two relays connected in series in the same circuit. It should be also pointed out that one complete 10 operation of the system controls and indicates all functions. This feature is particularly valuable where the time involved in making changes in the condition of the devices controlled by the office levers is of primary importance.

With my invention, the conditions of all devices may be changed during a single operation of the equipment and in the same time as would be required to change the condition of a single device.

Another advantage of my invention is that since the line circuits are in every instance opened at the location where energy is supplied to these circuits, that is, adjacent the battery source, it is unlikely that a faulty contact or imperfect insulation would result in a leakage current to hold up a relay which should be deenergized, thereby interfering with the proper operation of the system.

Finally, it will be noted that since the line 40 circuits are sectionalized, in case any failure occurs at one of the stations, the system will still operate satisfactorily between the office and the station at which the fault occurs. One advantage of this feature is that it assists in discovering the location of the failure because it indicates, by the failure of the system beyond the point of failure, the point at which the fault occurs. Another advantage of this feature is that the complete equipment is not thrown out 45 of service by this fault but all parts of the system between the location at which the fault occurs and the office can be operated at full efficiency.

As suggested above, the complete wire circuits here shown, may be replaced by circuits each 50 including one wire and a ground return, and it should be understood that in the following claims, the terms "line circuit", "line wire", etc. are intended to include circuits with ground return as well as complete metallic circuits.

Although I have herein shown and described only two forms of remote controlling apparatus embodying my invention, it is understood that various changes and modifications may be made therein within the scope of the appended claims 55 without departing from the spirit and scope of my invention.

Having thus described my invention, what I claim is:

1. A centralized traffic controlling system for 70 railroads comprising an office having a plurality of controlling devices, a first series of counting relays one for each controlling device, a plurality of control relays distributed at spaced points, a second series of relays one adjacent each said 75

control relay, means for transmitting impulses alternately from said office and said points in sequence, and means responsive to said impulses for operating the relays of said two series in order and in synchronism and effective when each relay of said first series is operated to condition the control relay associated with the corresponding relay of the second series in accordance with the condition of the controlling device 10 associated with the relay of the first series which is operated.

2. In combination, a line circuit, a series of counting relays, a plurality of movable devices, an indication relay, means for operating said 15 counting relays in order, means effective when each of said counting relays is operated to supply said indication relay with current under the control of a different one of said movable devices over said line circuit, and a plurality of other 20 relays each controlled by said indication relay when a corresponding counting relay is operated.

3. Remote controlling apparatus comprising a plurality of station relays, a line circuit normally including a contact of each said station 25 relay, a plurality of movable devices one for each station relay, means for operating said station relays in succession, an auxiliary relay associated with each said station relay and each arranged to be included in said line circuit when 30 the associated station relay is operated, and means operating when each station relay is operated to supply said line circuit with current under the control of an associated one of said movable devices for governing the auxiliary relay 35 then connected with the line circuit.

4. Remote controlling apparatus comprising a line circuit, a plurality of control relays normally disconnected from said line circuit but arranged at times to be connected with said line circuit in 40 succession, a plurality of movable devices one for each said control relay, an additional relay, and means controlled by said additional relay and operating when any of said control relays is connected with said line circuit to supply said line 45 circuit in series with said additional relay with current of a selected character depending upon the condition of the corresponding device, each control relay being responsive to the character of the current supplied thereto.

5. Remote controlling apparatus comprising a line circuit, a series of relays all normally disconnected from said line circuit, a plurality of movable devices one for each relay of said series, means operating in response to a change in the 55 position of any such device to connect the first relay of said series with said line circuit, means for connecting each remaining relay of the series with said line circuit when the preceding relay in the series becomes energized, means operating 60 when any relay of said series is connected with said line circuit to supply the line circuit in series with such relay with current of a selected character depending upon the position of the associated device, an auxiliary relay, means for 65 connecting said auxiliary relay with said line circuit when any relay of said series is connected with the line circuit, and a plurality of indication devices selectively controlled by said auxiliary relay in accordance with the relay of said 70 series which is operated and controlled in accordance with the character of the current supplied to said auxiliary relay.

6. Remote controlling apparatus comprising an office and a station connected by a line circuit, 75 a plurality of movable levers at the office, two re-

lays R¹ and OT at the office, a plurality of control relays at the station, a plurality of devices one controlled by each such control relay, a manually controlled starting key at the office, means set into operation when said key is actuated to supply said line circuit with current at said office in series with relay OT under the control of one of said movable levers, means for connecting a control relay at the station with said line circuit when such circuit is supplied with current through relay OT, means effective when said relay OT becomes energized for connecting relay R¹ with said line circuit, means effective when said control relay becomes energized to supply said line circuit at the station with current under the control of one of said devices, means operating when relay R¹ becomes energized to supply the line circuit with current at the office in series with relay OT under the control of a second one of said levers, means operating when relay OT is connected with the line circuit the second time for connecting a second control relay at the station with said line circuit, means operating after relay OT and said second control relay are energized to again supply relay R¹ with current over said line circuit under the control of a second device at said station, and a plurality of indicators successively controlled by relay R¹.

7. Remote controlling apparatus comprising a line circuit, a holding circuit, a relay S¹, a relay !WR, means for at times energizing relay !WR over said line circuit, means controlled by relay !WR for at times picking up relay S¹, means for subsequently holding relay S¹ energized over said holding circuit, a relay S², a relay !CH, means for at times energizing relay !CH over said line circuit, a pick-up circuit for relay S² controlled by relay !CH, a stick circuit for relay S² controlled by relays S¹ and !WR, movable devices 40 separately controlled by relays !WR and !CH, and indication means operated over said line circuit.

8. Remote controlling apparatus comprising a line circuit, a plurality of movable devices, a first relay responsive to the character of current supplied thereto, means for at times repeatedly operating said first relay over said line circuit each time by current of selected character depending upon the positions of a different one 50 of said devices, a chain of counting relays arranged to be operated in sequence by repeated operation of said first relay, and indication means controlled jointly by said first relay and by said counting relays.

9. Remote controlling apparatus comprising a line circuit, a plurality of movable levers and indication relays at one point, a plurality of control relays, a plurality of movable devices one controlled by each said control relay, and means for delivering to said line circuit a series of alternate control and indication impulses, each control impulse being of selected polarity governed by one of said movable levers for controlling an associated control relay and each indication impulse being of selected polarity governed by one of said devices to control an associated indication relay, and means responsive to each such impulse for preparing the apparatus to deliver the succeeding impulse in such series.

10. Remote controlling apparatus comprising a line wire connecting an office and a station, manually controlled means for at times supplying a starting impulse to said line wire, means operating in response to said starting impulse to de- 75

- liver a series of alternate control and indication impulses to said line wire, means selectively controlled by said control and indication impulses, and automatic means at said station for at times 5 delivering a starting impulse to said line wire.
11. In combination, a line wire connecting an office and a station, a movable device at said station, means operating in response to a change in the position of said device to deliver a starting 10 impulse to said line wire, means at the office responsive to said starting impulse to deliver another impulse to said line wire, means responsive to such other impulse for delivering to said line wire an indication impulse under the control of 15 said device, and indication means at the office selectively responsive to said indication impulse.
12. In combination, a first line wire connecting an office and a station, a movable device at said station, means operating in response to a 20 change in the position of said device to deliver a starting impulse to said first line wire, a second line wire connecting said office and station, means responsive to said starting impulse for delivering another impulse to said second line wire, means 25 at the station responsive to said other impulse to deliver to said first line wire an indication impulse under the control of said device, and means at the office selectively controlled by said indication impulse.
13. In combination, a first line wire connecting an office and a station, a movable device at said station, a normally deenergized relay D1 at the station, means operating in response to a change in the position of said device to deliver a 30 starting impulse to said first line wire over a back contact of relay D1, a second line wire connecting said office and station, means at the office responsive to said starting impulse for delivering another impulse to said second line wire, means 35 responsive to said other impulse for energizing relay D1, means operating when relay D1 is energized to deliver an indication impulse to the first line wire under the control of said device, and means at the office selectively controlled by said indication impulse.
14. In combination with a line wire, a series of 40 movable devices, means set into operation by a change in the position of any device to deliver to the line wire an indication impulse under the control of the first device in said series, a plurality of indicators one for each said device, means 45 responsive to each indication impulse to condition the associated indicator in accordance with such impulse and to connect the line wire with means for delivering an indication impulse under the control of the next device in said series, and means controlled by the last device in said series which has been operated to prevent the delivery 50 of indication impulses by succeeding devices in said series.
15. In combination with a first line wire connecting an office and a plurality of stations, a series of movable devices at least one located at each station, a plurality of transmitting equipments one for each said device, means set into 55 operation by a change in the position of any particular device for successively actuating the transmitting equipments for all devices in said series up to and including the particular device, means operating when any transmitting equipment is actuated to deliver to said line wire an indication impulse under the control of the corresponding device, and indication means at said office selectively controlled by said indication impulses.
16. In combination with a first line wire con- 60
- necting an office and a plurality of stations, a series of movable devices at least one located at each station, a plurality of transmitting equipments one for each said device, means set into operation by a change in the position of any particular device for actuating the transmitting equipment associated with the first device of said series, means operating when any transmitting equipment is operated to deliver to said line wire an indication impulse under the control of the 10 corresponding device, indication means at the office selectively responsive to each said indication impulse, and means controlled by each transmitting equipment and operating when any such equipment preceding said particular device in 15 said series is actuated to actuate the succeeding transmitting equipment.
17. In combination with a line circuit, a manually operable key, a relay R1, a chain of counting relays, a relay K, a pick-up circuit for relay 20 R1 arranged to be closed if said key is operated while relay K is deenergized, a pick-up circuit for the first relay of said counting chain including a front contact of relay R1, a pick-up circuit for relay K arranged to be closed if said key is restored to its normal position while the first relay of said counting chain is energized, means operating when said relay K is energized to deliver successive spaced control impulses to said line circuit, means selectively responsive to said 25 control impulses, means operating during the intervals between successive control impulses to deliver indication impulses to said line circuit, means responsive to successive indication impulses to energize successive relays in said counting chain, and indication means controlled by said counting chain and selectively responsive to said indication impulses.
18. Remote controlling apparatus comprising a line circuit, a series of control relays, a plurality of starting keys, a plurality of control devices, one for each said control relay and each associated with one of said starting keys, means set into operation when any starting key is operated for successively connecting the control relays of said series as far as the relay associated 40 with such key with said line circuit, and means effective when any control relay is connected with said line circuit to supply the line circuit with current under the control of the associated control device.
19. Remote controlling apparatus comprising a line circuit, a series of control relays, a plurality of starting keys, a plurality of control devices, one for each said control relay and each associated with one of said starting keys, stepping means set into operation when any of said keys is operated for successively connecting the control relays of said series with said line circuit, means operating when the control relay corresponding 45 to the operated key has been connected with said line circuit to prevent further operation of said stepping means, and means operating when any control relay is connected with said line circuit to supply the line circuit with current under the control of the associated control device.
20. Remote controlling apparatus comprising a line circuit, a plurality of control relays, a plurality of movable levers and indication relays at one point, a plurality of starting keys one for each said lever, a plurality of movable devices one controlled by each said control relay, and automatic means set into operation by a movement of any device or an operation of any key for delivering to said line circuit a series of alternate control and indication impulses each 50
- 75

control impulse being governed by one of said levers for controlling an associated control relay and each indication impulse being governed by one of said devices for controlling an associated indication relay, stepping means responsive to each such impulse for preparing the apparatus to deliver the succeeding impulse in such series, and means operating if said automatic means was actuated by operating a starting key 10 to prevent operation of said stepping means after the delivery of the control impulse governed by the corresponding lever, and means operating if said automatic means was actuated by a movement of one of said devices for preventing operation of said stepping means after the delivery 15 of the indication impulse governed by such device.

21. In a remote control system, an office and a station connected by a line circuit, a plurality 20 of devices at said station, control and indication means at said office for said devices, chains of counting relays at said office and at said station, respectively, means controlled by corresponding relays of said chains for transmitting 25 alternate control and indication impulses over said line circuit to control and indicate said devices sequentially, means controlled by each control impulse to operate corresponding relays of said chains to condition said line circuit for the 30 transmission of the next succeeding indication impulse, and means controlled by each indication impulse to operate corresponding relays of said chains to condition said line circuit for the transmission of the next succeeding control 35 impulse.

22. In a remote control system, an office and a station, a series of devices at said station, control levers and indication means at said office for said devices, a normally open line circuit 40 from said office to said station, normally inactive control means for closing said line circuit to transmit a control impulse from each of said control levers to operate the corresponding device, starting means for setting said control 45 means into operation to control the first device of said series, means responsive to each of said control impulses to open said line, means responsive to each opening of said line circuit following a control impulse to again close said 50 line circuit to transmit an indication impulse from one of said station devices to operate the corresponding indication means at said office, means responsive to each of said indication impulses to open said line circuit, and means responsive to each opening of said line following 55 an indication impulse to again close said line circuit to transmit a control impulse to the next device of said series whereby each of said devices are alternately controlled and indicated 60 in sequence over a single line circuit.

23. A remote control system of the synchronous step-by-step type comprising means for transmitting a series of stepping impulses over a line circuit from an office to a station, the 65 source of energy for the alternate impulses of said series being at said office and the source of energy for the intervening impulses of said series being at said station, a series of station devices, one for each alternate stepping impulse, means for controlling each station device according to the character of the corresponding impulse, a plurality of indication devices at said office, one for each intervening stepping impulse 70 and means for controlling each indication de- 75

vice according to the character of the corresponding intervening impulse.

24. In a signaling system, an office and a remote station connected by a line circuit, a series 5 of devices part at said office and part at said station, impulse transmitting means operating over said line circuit to actuate said devices in sequence each to a position selectively determined by a particular impulse, and means controlled immediately by each of said impulses for 10 selecting the device to be operated by the next succeeding impulse.

25. In a signaling system, two stations connected by a line circuit, a series of devices at each 15 of said stations each adapted to be actuated by a line impulse transmitted over said line circuit from the other station, means for transmitting a series of impulses over said line circuit alternately from said two stations, each to 20 actuate a particular device, chains of relays one at each of said stations, means for actuating equivalent relays of said chains in response to each of said impulses, and means controlled by said equivalent relays when actuated for conditioning a particular device of said series for 25 operation by the next succeeding impulse over said line circuit.

26. In combination, an office and a station, a chain of counting relays and a series of devices at said office, a chain of counting relays and a 30 series of devices at said station, a line circuit connecting said office and station, means controlled by said chains of counting relays for repeatedly closing said line circuit to transmit impulses over said line circuit, receiving means re- 35 sponsive to said impulses received over said line circuit to selectively actuate said devices sequentially and alternately at said office and at said station, sending means responsive to each impulse transmitted over said line circuit to terminate such impulse, and means responsive to the alternate operation of said receiving and sending 40 means for actuating the counting relays of said chains sequentially.

27. A remote control system comprising an office and a plurality of stations, a synchronous selector located at the office, and a synchronous selector with portions thereof at each of said stations, means for operating said office synchronous selector in synchronism successively 45 with each of said station synchronous selectors comprising a supplemental selector at each of said stations, that at the first station being controlled by the synchronous selectors at the office and at said first station, and that at each remaining station being controlled by the synchronous selectors at such station and at the next preceding station.

28. In a remote control system comprising an office and a series of stations connected by a line 60 wire, a selector at the office, a selector at each station, means for synchronously operating the selectors at the office and at each station comprising apparatus for transmitting a group of impulses alternately from the office to one of the stations and from said one station to said office over said line wire to operate the selectors at said office and said one station in synchronism, means controlled by the selector at said 65 one station and effective at the completion of said group of impulses to disconnect the line wire from the selector at said one station and to complete the line wire from the office selector to the selector at the next station of the series to 70 75

initiate the transmission of a group of impulses to said next station.

29. In a remote control system comprising an office and a series of stations connected by a line circuit, a selector at the office, a selector at each station, means for synchronously operating the selectors at the office and at each station comprising apparatus for transmitting a group of impulses from the office to one of said stations over said line circuit to actuate the selector at said one station in synchronism with the office selector, means at each station for switching said line circuit to the office from said station to the next station at the completion of said group of impulses and for initiating the transmission of a group of impulses from the office to said next station to actuate the selector at said next station in synchronism with the office selector, and means at each of said stations to initiate the operation of said office selector to effect the operation of all of said station selectors in sequence. 10

30. In a centralized traffic controlling system for railroads, in combination, an office and a plurality of stations, a series of devices at said stations including at least one device at each station, means including selector apparatus at said office and at each of said stations to successively indicate at said office the condition of each of said station devices, means at each of said stations for setting said selector apparatus into operation to indicate the condition of a device at such station, and means responsive to the operation of said selector apparatus when indicating the condition of any station device for setting said selector apparatus into operation to indicate the condition of the next succeeding station device. 15

31. In a remote control system including an office and a plurality of stations, a selector comprising a chain of counting relays at said office, a second selector comprising a chain of counting relays of which certain ones are at each of said stations, said selectors being normally deenergized and adapted when operated to close a series of contacts in sequence and to close corresponding contacts of different selectors simultaneously, means for transmitting impulses from said office to each of said stations in turn to operate said contacts in sequence, means controllable from said office or from any of said stations for initiating operation of said means; means at each station for controlling devices at such station by the contacts of the associated selector contacts and by said impulses. 20

32. A selector of the relay chain type, comprising a series of counting relays, a pair of normally deenergized line relays, a normally deenergized slow release relay adapted to be picked up when one of said line relays is first energized and to be maintained in the energized position when the other of said line relays is energized repeatedly; pick-up circuits for each of said counting relays, the circuits for consecutive relays being connected to the contacts of said line relays alternately, each of said circuits except the first including a normally open front contact of the next preceding counting relay, the first circuit including a back contact and the remaining circuits each including a front contact of said slow release relay; a holding circuit for each counting relay including a back contact of the next succeeding counting relay, and means for energizing said two line relays alternately to energize said counting relays one at a time in sequence. 25

33. In a remote control system, means for

transmitting a series of impulses over a line wire to a remote station comprising a pair of line relays, starting means for energizing the first of said relays by a momentary impulse; means effective when said first relay becomes energized for preparing a circuit for the second relay, said circuit including a source of energy, a back contact of said first relay, and said line wire and becoming closed when the first relay is released to energize said second relay and to initiate the transmission of an impulse over said line wire; means effective when said second relay becomes energized to open said line wire to terminate said impulse and to then close a circuit through said line wire and said first relay; means at the remote station responsive to the termination of said first impulse for transmitting a second impulse to said line wire to again energize said first relay for repeating the above described cycle of operations. 30

34. A remote control system comprising a series of stations and an office, line circuits for connecting each of said stations in turn with said office, a device at each of said stations, a selector relay and an indication stick relay for each device at said office, a pick-up circuit for each indication relay including a front contact and a holding circuit including a back contact of the corresponding selector relay, means for energizing said selector relays in sequence, line controlled means effective when each selector relay is energized for closing the pick-up circuit of the corresponding indication relay, and means for controlling said line controlled means selectively according to the condition of the corresponding device at the remote station. 35

35. Means for continuously indicating whether or not each of a series of contacts is closed, each said contact being located at the remote end of an intermittently rendered available line circuit, comprising a stick relay for each contact, each having a pickup circuit and a holding circuit, means effective when any of said contacts is opened or closed for briefly opening the holding circuit of the corresponding stick relay, and other means operating over said line circuit and effective during the time that said stick relay is open to control the pickup circuit for said stick relay selectively in accordance with the position of the associated contact of said series. 40

36. A centralized traffic controlling system for railroads comprising an office and a plurality of traffic governing devices located along the track-way, a plurality of relays at the office one for each said device, a pickup circuit and a holding circuit for each said relay, apparatus for rupturing all said holding circuits one at a time in a predetermined sequence, another relay at the office, means for successively placing said other relay under the control of said devices, and means for controlling the pickup circuit of each stick relay by said other relay when the stick circuit for such relay is open. 45

37. A centralized traffic controlling system for railroads comprising an office and a plurality of traffic governing devices located along the track-way, a plurality of relays at the office one for each said device, a pickup circuit and a holding circuit for each said relay, apparatus for rupturing all said holding circuits one at a time in a predetermined sequence, a polar relay at the office, means controlled successively by said devices for energizing said polar relay in one direction or the other in accordance with the position of the device, the pickup circuit for each stick relay including a 50

polar contact of said polar relay and being available only when the stick circuit for such stick relay is ruptured.

38. In a remote control system, an office and a plurality of stations connected by a normally open line circuit including a pair of line wires and a line relay at the office, starting means at each station for closing the portion of said line circuit extending from said station to the office to energize said line relay, sectionalizing means at each station effective when operated to open the portion of the line circuit leading from the office through said station to the next succeeding station, and to complete a message circuit including said line wires for communication between the office and said station, means responsive to the energization of said line relay by said starting means to operate the sectionalizing means at the first station, and means responsive to the energization of each message circuit for restoring the sectionalizing means at the corresponding station and for operating the sectionalizing means at the next succeeding station, whereby communication between the office and each station in turn is established in response to the operation of the starting means at any station.

39. In a remote control system, an office and a plurality of stations connected by line wires, a series of movable devices at least one located at each station, means set into operation by a change in position of any one of said devices for transmitting an impulse from the office to the station nearest the office, means at each station rendered effective when an impulse transmitted to such station is terminated for transmitting a return impulse from such station to the office, and for then initiating the transmission of an impulse from the office to the next station more remote from the office, means at each station controlled in accordance with the position of the movable device at such station for determining the character of the impulse transmitted from such station, indication means at the office for said movable devices, and means for controlling said indication means in accordance with the character of said impulses.

40. A remote control system comprising an office and a plurality of stations connected by a line wire, a transmitter contact at each station, means at each station for closing the contact at said station to transmit current over the line wire to the office when said line wire is available, means at each station responsive to the flow of current in said line wire to open said contact and to then close the line wire from the office through said station to render the line wire available at the next station more remote from the office, means at each station for controlling the character of current transmitted from such station, and indication means at the office for each station selectively responsive to the character of current transmitted from such station.

41. A remote indication system for railroads comprising a plurality of devices distributed at different stations along a railway, a plurality of intermittently available line circuits each including the same line wire for connecting each of said station devices with an associated device at the office, impulse transmitting means adapted to operate over said line circuits, means controlled over said line wire and responsive to a change in condition of any of said devices to set said impulse transmitting means into operation to transmit a series of impulses for selecting each station device in turn and including means responsive to

each impulse of said series for transmitting a return impulse to select each office device in turn, means for controlling the station devices each in accordance with the character of a selected impulse of said series, and means for controlling the office devices each in accordance with the character of a selected return impulse. 5

42. In combination with a line circuit, a winding and front contact of a line relay in said line circuit, stepping means adapted to be operated in response to repeated deenergization and reenergization of said line relay, and means controlled by said stepping means effective when said line relay has been deenergized to close a shunt around said front contact until said line relay again becomes energized. 10

43. In combination, a pair of line circuits each including the same line wire and arranged to be closed alternately, the first including the winding and a front contact of a first line relay, and the second including the winding of a second line relay and a back contact of said first line relay, stepping means operated progressively in response to the alternate energization and release of said two line relays, and means controlled by 20 said stepping means effective when either line relay has been energized and released for preparing the line circuit for the other line relay, whereby said other line relay may be energized and released. 25

44. In combination, a pair of line circuits each including the same line wire and arranged to be closed alternately, the first including the winding and a front contact of a first line relay, and the second including the winding of a second line relay and a back contact of said first line relay, stepping means operated progressively in response to the alternate energization and release of said two line relays, means controlled by 35 said stepping means for closing a shunt around the front contact in the first line circuit when the second line relay is released, and means for opening said shunt when the first line relay becomes energized. 40

45. A synchronous selector remote control system comprising a stepping line wire, a pair of line relays arranged to be energized alternately and repeatedly, a chain of counting relays arranged to be energized one at a time in sequence as said line relays are energized alternately, a 50 series of control circuits, one for each alternate counting relay, each including a front contact of said counting relay, the winding of one line relay and said line wire, a series of indication circuits, one for each intervening counting relay, each including a front contact of said intervening counting relay, the winding of the other line relay and said line wire, means for transmitting distinctive impulses over said control and indication circuits, means responsive to said impulses to operate said 55 line relays, and means controlled by said line relays to operate said counting relays. 60

46. A synchronous selector remote control system comprising an office and a plurality of stations, a synchronous selector at the office, a synchronous selector having a portion at each of said stations, a plurality of stepping circuits completed successively and each including a stepping wire for effecting operation of each of said station selectors in synchronism with a corresponding portion of the office selector, said selectors being normally at rest in a zero position, means for transmitting a plurality of messages successively over said stepping circuits during operation of said selectors, and means including said stepping 70 75

wire and effective at each station provided said selectors are at rest in their zero position for initiating the operation of said selectors.

47. A synchronous selector remote control system comprising a stepping line and a message line, a line relay in said stepping line, a chain of counting relays arranged to be energized one at a time in sequence as said line relay is actuated repeatedly, a series of control circuits, one for each alternate counting relay, each including said message line and a contact of the corresponding counting relay, a series of indication circuits, one for each intervening counting relay, each including said stepping line and a contact of the corresponding counting relay, means for transmitting distinctive control impulses over each of said control circuits, and means for transmitting distinctive indications over each of said indication circuits.

20 48. A synchronous selector remote control system comprising an office and a plurality of stations, two series of stepping contacts, one at the office and the other at the stations, each adapted to be closed one at a time in sequence for rendering available a series of control message circuits from the office to each station in turn during a single cycle of operation of said contacts, a plurality of stick relays at the stations, including one for each message circuit, and at least one at each station, a plurality of stick relays at the office including one for each station, means rendered effective during said cycle of operation of said contacts to complete selected message circuits to pick up selected ones of the stick relays at a station if and only if the office stick relay for said station is energized, means for selectively picking up said office stick relays, means for initiating the operating cycle of said contacts, and means controlled by said contacts for releasing said office stick relays.

49. In a centralized traffic controlling system for railroads, a control office, a plurality of field stations, a stepping circuit and a message circuit extending from the control office to the several stations, means in the control office manually controllable by the operator for applying to the stepping circuit one at a time a plurality of different combinations of impulses, each combination of impulses being characteristic of a particular station and the controls for that station, and means at each station for governing the energization of the message circuit when said impulses are applied to the stepping circuit for a particular station to conform with the indications to be transmitted from that station to the control office.

50. In a system of the type described, a control office, a field station, a stepping circuit connecting the control office and the field station, means for energizing said stepping circuit with time spaced impulses of selected polarities, step-by-step means at the field station responding to take one step for each of said impulses irrespective of its polarity, and means at said field station distinctively controlled on each step in accordance with the polarity of the impulse for that step.

51. In a centralized traffic controlling system for railroads, a control office, a plurality of field stations, a stepping wire extending from the control office through the several stations, means in the control office for energizing said stepping wire with a series of time-spaced impulses of selected polarities, and a bank of stepping relays at the stations operated one at a time and one for each time the stepping circuit is energized by

an impulse irrespective of the polarity of that impulse.

52. In a centralized traffic controlling system for railroads, a plurality of stations, a circuit connecting said stations, means placing a plurality of series of positive and negative impulses on said circuit each series comprising a predetermined number of impulses, and means determining whether a particular impulse shall be positive or negative, whereby the number of said 10 distinctive series constituting said plurality of series is equal to two raised to the power of a number equal to the predetermined number of impulses in a series.

53. In a centralized traffic controlling system 15 for railroads, the combination with a stepping line and a message line connecting an office and a plurality of stations, a series of relays in said office operated successively in response to a series of impulses each of controllable character impressed upon said stepping line, means associated with said series of relays and responsive to each impulse to determine the character of the next succeeding impulse, means at the stations selectively controlled in accordance with the 25 character of said impulses, and means at the office controlled by said stepping relays for indicating traffic conditions at said stations over said message line.

54. In a centralized traffic controlling system 30 for railroads, a control office, a field station, a line circuit connecting said control office with said field station, a plurality of traffic controlling devices at said field station, a plurality of control levers at said control office corresponding to said traffic controlling devices, means for impressing a series of impulses on said line circuit having positive and/or negative polarities in accordance with the positions of said levers, relay means at said field station repeating each impulse of said 40 series irrespective of its polarity, a series of stepping relays at said field station operated step-by-step by said relay means, contact means at said field station repeating the polarity of each impulse of said series, and an electro-responsive 45 device at a field station for each step controlled by said contacts on that step in accordance with the polarity of the impulse repeated thereby.

55. In a centralized traffic control system for railroads, a control office, a field station, a line 50 circuit connecting said control office with said field station, means for impressing a series of time spaced impulses on said line circuit, step-by-step means at said control office and at said field station, relay means at said office and at said 55 field station repeating the impulses of said series irrespective of the polarity of such impulses, means controlled by said relay means for causing their respective step-by-step means to operate one step for each impulse, manually governable means at said control office for selectively determining the polarity of each impulse of said series, contact means at the station repeating the polarity of each impulse of said series, and an electro-responsive device at the field station for each step controlled by the contact means on that 65 step in accordance with the polarity of the impulse repeated thereby.

56. In combination, a line wire connecting a local office and a distant way station of a railway 70 system, a source of energy at each end of said line circuit, a control relay at said way station, an indicating relay at said office, a way station series relay included in series with the way station source when said indicating relay is energized, an 75

- office series relay included in series with said office source when said control relay is energized, and means for excluding said respective series relays from said respective sources.
- 5 57. In combination, a line wire connecting a local office and a distant way station of a railway system, a traffic controlling device at said way station, a source of energy at each end of said line circuit, a control relay at said way station for controlling said traffic controlling device, an indicating relay at said office, a way station series relay included in series with the way station source when said indicating relay is energized, an office series relay included in series with said office source when said control relay is energized, and means for excluding said respective series relays from said respective sources by momentary opening of said respective energizing circuits.
- 10 58. In a remote control system, two stations connected by three conductors, at least two operating units units at one of said stations, and means for transmitting over the conductors in a single impulse a control signal indicating the desired one of three possible operations for one operating unit and the desired one of two possible operations for a second unit.
- 15 59. In a remote control system, two stations connected by three conductors, groups of operating units, and means for transmitting over the conductors in a single impulse a report signal indicating one of three conditions in one operating unit or group and one of two conditions in a second unit.
- 20 60. In a train dispatching system, a control station and substations connected by three line wires, signalling units at the control station, one for communication with each substation, and concatenated distributing switches at the control station for associating the signalling units successively with the line wires and for establishing successive impulse periods for each unit.
- 25 61. In a train dispatching system comprising a control station and substations connected by three line wires, receivers at the control station, one for each substation for reception of supervisory signals, and concatenated distributing switches for associating the receivers successively with the line wires and for establishing successive impulse periods during the association of each receiver, successive control and report impulse periods being established during each such association.
- 30 62. In a train dispatching system comprising a control station and substations connected by three line wires, a receiver at the control station responsive to current combinations in the line wires adapted to respond selectively during a single line impulse to one of three positions of one selector at a substation and to one of two positions of a second selector at a substation.
- 35 63. In a train dispatching system, a control station connected by three line wires to a substation, a plurality of units at the substation, and a sender at the substation adapted to transmit during a single line impulse a supervisory signal indicating one of two conditions of one unit and one of three conditions of another unit.
- 40 64. In a train dispatching system comprising a control station and a substation connected by three line wires, a receiver at the control station and a receiver at the substation, means at the control station for controlling the receiver at the substation, and a sender located at and responsive to the receiver at the substation for trans-
- mitting signal impulses isochronously with said receiver at the control station.
- 45 65. In a train dispatching system, stations connected by three line wires, a source of current, means at each station for variably applying current from said source to said line wires, a receiver at one station comprising a polar and a neutral relay, the polar relay actuated by current in one line wire to close one or another circuit when the line current is positive or negative and neither relay actuated when the current is zero, the neutral relay, actuated by local energy through the contacts of the polar relay, being released to close a third circuit when the line current is zero, and traffic controlling devices at said stations variably operated upon the closing and opening of said circuits.
- 50 66. In a centralized traffic control system for railroads, the combination of a stepping line wire, a message line wire and a common return wire connecting an office and a plurality of stations, means in the office for impressing upon the stepping line wire and the common return wire a series of impulses each of controllable polarity, receiving means at each of the stations controlled in accordance with the polarity of the impulses of said series, control levers and indication means at said office, traffic controlling means at a particular station, and means controlled by said receiving means and acting through the medium of said message line wire and common return wire for at times controlling said indication means in accordance with conditions at such station and for at other times controlling said traffic controlling means in accordance with the positions of said levers.
- 55 67. A selector system for transmitting controls from an office to a plurality of stations and for receiving indications at said office from any one of said stations comprising, a stepping line connecting the office and said stations, means for impressing a series of impulses each of controllable character upon said stepping line, stepping relays at the office and at said stations operable sequentially by said impulses, a message line connecting the office and said stations, means at the stations selectively controllable in accordance with the character of said impulses, a plurality of indication devices at said office, means controlled by said stepping relays for controlling a selected one of said indication devices to one position or another depending upon whether said message wire is energized or not on a particular step during the operation of said relays, and means controlled by traffic conditions at a selected station for controlling the energization of said message wire on said particular step.
- 60 68. In a centralized traffic controlling system for railroads, a stepping line and a message line connecting an office and a plurality of stations, means in the office for impressing a series of positive and/or negative impulses sequentially upon said stepping line, means at a particular station selectively responsive to the polarity of selected impulses of said series, indication means at the office for each station, and means controlled by said selected impulses for controlling the indication means for said particular station over said message wire in accordance with conditions at such station.
- 65 69. In a communication system of the multiple impulse type for centralized traffic control, a stepping line circuit including a line relay, a chain of neutral stepping relays arranged in two groups which relays are operated sequentially by

the operation of said line relay, means energized in response to the operation of said stepping relays for opening and closing said line circuit, a selector relay, means for causing operation of said second group of stepping relays following operation of the first group if said selector relay is in a predetermined condition, and means for controlling said selector relay from a distant point.

70. In a normally at rest remote control system of the code selective type, a control office, a plurality of field stations, a normally deenergized

first line and a plurality of other lines connecting said control office with said field stations, means for energizing said first line at said office to start the system into a cycle of operation, means at said control office effective during said cycle for applying distinctive impulses to said first line in series with said other lines in different combinations, and means at each of said stations selectively responsive to said distinctive impulses and said different combinations of said first line during the cycle. 5 10
